AUTOMATIC CIRCUIT BREAKER

Wayne E. Jenkins, Los Angeles, Calif., assignor
to Domestic Manufacturing Company, Inc.,
Los Angeles, Calif., a corporation of California

Application January 13, 1939, Serial No. 250,785

5 Claims. (Cl. 200—138)

This invention relates broadly to automatic temperature-responsive devices and has to do more especially with contact makers and breakers which operate automatically in conformity 5 with predetermined temperature changes.

The object of this invention is to provide a durable and reliable, but inexpensive safety accessory for use in conjunction with gas and oil-fired furnaces and the like, having pilot burners 10 for re-lighting the main burners and in which the main burner automatic fuel-control valves are electrically actuated—the function of the safety accessory being to open the main burner fuel-control circuit in event of a failure of the 15 pilot flame and to keep said circuit open until the pilot flame is re-established—thus preventing the gas or other fuel being turned on when there is no pilot flame to ignite it.

Probably the simplest, cheapest and most compact type of thermostatic element ever devised is the familiar bi-metallic plate, consisting of two different metals, superimposed and having different expansion co-efficients. But elements of that kind have not heretofore been considered 25 practicable for subjection to considerable temperatures (such as the temperature prevailing in or immediately adjacent a pilot flame) because at such temperatures they lose, in whole or in part, their elasticity and cannot then be subjected to flexure without being permanently deformed. And since the usefulness of a thermostatic element is generally dependent upon its 30 ability fully to restore itself to its initial form or condition, it is manifest that any element which 35 may become permanently deformed under prevailing operating conditions is wholly unsatisfactory.

The present invention overcomes the afore-stated deficiency of bi-metallic plate when subjected to relatively high temperatures in that it 40 provides an arrangement wherein there is no distorting force applied to the thermostatic element when its temperature is such as to cause its elasticity to be materially impaired or destroyed—the force tending to distort being applied to the element only when its temperature is low enough to ensure against permanent distortion. How this is accomplished can best be explained by reference to the drawing and 45 temporaneously with the detailed description of the device illustrated.

Another feature of my present invention is the outgrowth of great difficulty which I experienced in developing a spring-actuated device which is 50 very compact and at the same time capable

of withstanding the high temperature to which it normally is subjected in operation—due to its close proximity to a hot pilot flame. Various springs and spring arrangements which I first tried and which could conveniently have been 5 utilized in the space available were found to be unworkable because they lost their temper and ceased to be springs. But after protracted trials I discovered a solution to this difficulty in the provision of a leaf spring so situated as to be 10 partly protected from the heat of the pilot flame and so supported that the heat which it receives is rapidly conducted away—thus keeping the temperature of the spring down to a safe level.

Other features of this invention reside in the 15 simplicity and arrangement of parts which contribute to compactness, ease of assembly, reliability and cheapness of manufacture—all of which will become apparent as the detailed 20 description progresses.

In the drawing:

Fig. 1 is an elevational view of an automatic temperature-responsive circuit breaker in accordance with the preferred embodiment of the invention;

Fig. 2 is a sectional view taken along the line 2—2 of Fig. 1 and showing the contacts open;

Fig. 3 is the same as Fig. 2 except that the pilot is lighted and the contacts closed;

Fig. 4 is an enlarged section taken along the 30 line 4—4 of Fig. 1; and

Fig. 5 is a detail view taken along the line 5—5 of Fig. 2.

1 and 2, respectively, are contact points which are included in the control circuit of an electrically operated valve (not shown) which controls the flow of gas or other fuel to the main burner (also not shown) of a furnace or other heating device. Said contacts are continuously closed so long as the pilot remains lighted and are intended to open automatically if and when the pilot flame is extinguished. And, when open, they serve to prevent opening of the main fuel valve by interrupting its actuating circuit. Contact point 2 is fixed, being welded to the end of 45 a screw 3, which is a component part of a binding post 4, to which a conductor 5 is shown connected. Binding post 4 and screw 3 are insulated from the frame casting 6—which latter is provided with two holes 7 and 8 by means of 50 which it may be mounted on a main burner or other convenient support.

Frame casting 6 is provided with an opening at 9 for the reception of a pilot tube 10, which is held in place by means of a setscrew 11. Gas 55

is supplied through a conduit 12 to the pilot tube, and the latter is orificed at its upper end to form a burner tip. In Fig. 3 the pilot flame is depicted at 13.

5 Frame casting 6 includes two parallel, vertical members 6a and 6b which are connected by cross-pieces 6c and 6d.

10 Bridged between cross-pieces 6c and 6d and secured thereto by screws 14 is a plate 15 which I shall refer to as an abutment plate because it serves as an abutment for a thermostatic element 16—which is a bi-metallic strip, normally bowed, as per Fig. 2, and curved at its two extremities where it abuts plate 15.

15 Thermostatic element 16 is not attached to abutment plate 15, but it is bifurcated at its upper end, that is at 16a, so as to straddle a pin 17 which is pressed into abutment plate 15 and serves to secure element 16 against rotation 20 about its shaft 18.

25 Element 16 is rivetally secured to one end of shaft 18, together with a strip of stainless steel 19 which serves as a shield between the pilot flame and the thermostatic element, so as to prevent the flame impinging directly upon the latter.

30 Shaft 18 is a loose fit in a bushing 20 which is rivetally secured to plate 15 and said shaft is slideable axially in said bushing, as well as being rotatable therein.

35 Anchored to the upper cross-piece 6c by means of screws 14 and nuts 21 is a contact arm 22, consisting of a strip of stainless steel, to which contact arm is secured the contact point 1.

40 A stainless steel leaf spring 23 is secured at its lower end between cross-piece 6d and abutment plate 15, and its free upper end bears against contact arm 22, tending continuously to move the latter toward the fixed contact 2 so as to bring the two contact points into engagement—as shown in Fig. 3.

45 A small pin 24 extending transversely of and carried by shaft 18 engages the back surface of contact arm 22.

50 When cold, element 16 assumes the curvature shown in Fig. 2, and being itself a spring of greater force than the leaf spring 23, the contact arm 22 is held in the open contact position of Fig. 2.

55 When the pilot is lighted, element 16 straightens out, as shown in Fig. 3, and leaf spring 23 is then able to flex contact arm 22 to the closed-contact position, per Fig. 3. If heated still further, element 16 will assume a curvature opposed to the normal curvature shown in Fig. 2; and in order that it may do so without interference, shield 19 is curved as shown.

60 The thermostatic element is so proportioned that it will completely straighten out before it gets hot enough for its elasticity to become impaired; and when thus straightened out, it no longer bears against the abutment plate 15 at its extremities and the only force then acting upon it is the pull of shaft 18 which acts only at the 65 center—there being no force tending to flex the element and distort it. Any considerable flexing force applied to the element 16 when it is hot enough to have lost its elasticity would permanently distort it; and if the distortion thus produced were considerable it would render the device inoperative—as will be self-evident.

70 In the development of the present device, one of the major problems encountered was the provision of a spring for actuating the contact arm, which would not be impaired by the prevalent

high temperature, and with which simplicity of design and compactness could be achieved. A coil spring surrounding shaft 18 would get too hot and therefore lose its temper. And the same thing would happen to the contact arm if that 5 were to be employed as a spring. But, after much discouraging experimentation, I ultimately discovered that by securing the leaf spring 23 to the frame casting at a point well below the pilot flame and situating it behind the abutment plate 10 15—where it is partially shielded from the pilot—the heat which it receives is conducted away rapidly enough to ensure that the spring will not lose its temper.

15 The device of the present invention has to be 20 sold, if at all, in a highly competitive market where price is a controlling factor; and at the same time it must be completely dependable in operation for a long period of time. Otherwise expressed, the device must be as dependable 25 as it is possible to make it, regardless of price and substantially as cheap to manufacture as the lowest priced competitive device. For that reason, costly parts and machining operations must be avoided as far as possible, and the design must be such as to reduce the assembling, testing and adjusting operations to a minimum 30—for these all enter into the cost of production.

35 It will be observed that, save for one light casting, involving the simplest of machining operations, all the components of my device are simple punchings and screw machine parts; and it will be apparent that the assembling operations entail very little labor. And, in this connection, one outstanding feature which I wish 40 to point out is that the elements 15, 16, 18, 19, 20 and 24 constitute a self-contained unit which is separately assembled before mounting on the frame casting, and that the contact arm 22 is provided with an oblong opening 25 (see Fig. 5) 45 which permits insertion therethrough of the end of shaft 18 and pin 24, when turned at an angle of ninety degrees from the normal position shown in Fig. 5. The final assembly is thus greatly simplified because it is much easier to 50 insert the pin 24 in shaft 18 before mounting plate 15 on the frame casting than to do so afterward.

55 What is claimed is:

1. A temperature-responsive device comprising: a bowed bi-metallic strip, an abutment against which the two end-portions of said strip normally bear, said end-portions being unattached to said abutment and free to slide along the surface thereof, a supporting member attached to said strip intermediate the ends thereof and extending laterally therefrom, said supporting member being movable in a direction which is substantially normal to the plane of said strip, when said strip is straightened out, 60 and a spring acting on said supporting member and thereby continuously urging said strip toward said abutment, said strip being free to assume a curvature opposite to its normal curvature and having a tendency so to do in response to rising temperature.

65 2. A device in accordance with claim 1 wherein the said supporting member constitutes the sole supporting means for said strip.

70 3. A device in accordance with claim 1 wherein the said supporting member is a shaft journaled to slide axially and having one end secured to said strip approximately midway between the two extremities thereof and wherein said spring is a leaf spring, said spring being situated be- 75

hind said abutment and anchored at a point somewhat remote from said strip, the free end of said leaf spring being operative upon said shaft.

- 5 4. A temperature-responsive device comprising: an abutment plate, a bowed bi-metallic strip the two extremities of which normally bear against one side of said plate, a shaft journaled in and extending transversely through said plate, 10 said shaft being movable axially relatively to said plate and having one end secured to said stop midway between the extremities thereof, a leaf spring situated behind said abutment plate and operatively acting upon said shaft so as to 15 continuously urge said strip toward said abutment plate, and mechanism to be actuated in conformity with temperature changes affecting said strip, said mechanism being connected with said shaft and actuatable thereby, said strip 20 having a tendency to straighten in response to rising temperature and thereafter to assume an opposite curvature as the temperature rises further, said strip being free to assume an opposite curvature.
- 25 5. A temperature-controlled automatic circuit-breaker including a pair of contacts at least one of which is movable to make and break contact with the other, said circuit-breaker com-

prising a frame, a movable contact arm supported by said frame and carrying one of said contacts, the movements of said contact arm serving to make and break contact, a bowed bi-metallic strip, an abutment plate attached to said frame and interposed between said strip and said contact arm, the two extremities of said strip normally bearing against said abutment plate, a shaft journaled in said abutment plate and extending laterally therethrough, said 10 shaft being slidably axially, said shaft being secured to said strip intermediate its extremities and constituting the sole support for said strip, said shaft being connected with said contact arm, a leaf spring continuously urging said contact arm, together with said shaft and said strip, in a direction such as to bring about interengagement of said contacts and also to press the extremities of said strip against said abutment plate, said strip, when cool, being operative as a 15 spring to oppose said leaf spring and thus to retain said contact arm in open-contact position, said strip being operative when subjected to a rising temperature to straighten out and thus permit said leaf spring to move said contact arm toward its closed-contact position. 20
